UNITED STATES PATENT OFFICE.

JOSEPH DIVORA, OF PERU, ILLINOIS.

CULTIVATOR.

SPECIFICATION forming part of Letters Patent No. 292,996, dated February 5, 1884.

Application filed July 28, 1883. (No model.)

To all whom it may concern:

Be it known that I, JOSEPH DIVORA, of Peru, in the county of La Salle and State of Illinois, have invented certain new and useful Improvements in Cultivators; and I do hereby declare the following to be a full, clear, and exact description of the invention, such as will enable others skilled in the art to which it appertains to make and use the same.

My invention relates to an improvement in combined cultivators and stalk-cutters, the object being to provide a device of this character which shall combine simplicity and economy of construction with durability and efficiency in use; and with these ends in view my invention consists in certain details of construction and combinations of parts, as will be herein-after described, and pointed out in the claims.

In the accompanying drawings, Figure 1 is a top plan view of my improvement. Fig. 2 is a sectional view thereof. Fig. 3 is a rear elevation. Fig. 4 is a detached view of the cultivator, and Fig. 5 is a detached view of the stalk-cutter.

A represents the axle, preferably shaped as shown, being formed with a central arch and an inverted arch on each side thereof, the wheels B being journaled on the ends. To the central arch of this axle is secured the tongue C, which is of the ordinary split form, and to which is secured the cross-bar D. A cross-bar, E, bridges the two end arches, being rigidly secured to the sides thereof, and provided with a series of perforations, a, which register with perforations b in the lower arms of the end arches of the axle. In these perforations a and b are adapted to fit the ends of the perforated standards F, the said ends being decreased in size to fit the said perforations, thereby forming shoulders on the standards, which are adapted to retain them in their proper positions. To the upright standards F are secured the drag-bars G, the forward end of each of which is provided with a slot, in which fits the standard F, a bolt, c, passing through both and loosely securing them together. It will be readily seen that by thus connecting the standards F to the axle A the drag-bars G are allowed a free lateral movement, and from their connection to the standard they are also permitted a free vertical movement. The rear ends of these bars are

connected by the sectional yoke L, the two sections being bolted or otherwise secured together. By this arrangement it will be observed that the two bars G have a free lateral and vertical movement, but always retain the same relative position. The inner ends of the two sections of the yoke L are provided with perforations and the two parts locked together. When it is desired to bring the rear ends of the bars G together, it is simply necessary to remove the bolt or screw h, thereby releasing the two sections of the yoke L and permitting the bars G to approach each other, which may then be locked, as before described. The bars G are provided with bearings i, in which are journaled the shafts j, to which are secured the bars k, the crushers M being secured to the latter. The said crushers are preferably constructed as shown, the blade being bent or twisted at an angle with the handle. It will now be readily seen that when the machine is to be used for crushing clods a free lateral and vertical movement is afforded to bars G, the latter always retaining the same relative position, and being guided by the handles s. The crushers M are also allowed an adjustment in their bearings, being permitted, by simply loosening the nut n, to be turned as desired.

Secured to the tongue C is the bell-crank T, pivoted at t, the lower arm of which is provided with a hook, the same being formed by turning up the end of the arm, which hook is adapted to hold the yoke L.

When it is desired to move the machine without dragging the crushers, the driver, sitting in the seat S, simply pushes from him the handle of the bell-crank, which raises the yoke L and lifts the crushers M from the ground. If desired, the bell-crank may be secured in this position by means of the dog U, pivotally secured at one end to the upright arm of the bell-crank, the other end being hook-shaped, adapted to engage in notches u, formed in the tongue C, and so retain the yoke in any desired adjustment.

Fig. 4 shows a view of the cultivator, which may be substituted for the clod-crusher, when so desired, by simply removing the bolt c, thereby releasing the drag-bars. This cultivator is provided with the drag-bars K, similar in construction to the drag-bars G, to which latter

are secured the handles H and also the depending standards I, provided on their lower ends with the shovels J, each succeeding standard being placed a little farther back and on 5 opposite sides of the drag-bars G, and being strengthened by the braces d. To the inner side of each drag-bar is secured the standard e, preferably bent into the shape shown, and provided on the lower end with a shield or 10 deflector, f, adapted to prevent the earth from being thrown between the two inner shovels on the adjacent drag-bars.

My improvement is also adapted to be used as a stalk-cutter by simply detaching the bars 15 G or K from the standards F and securing to the latter the bars N of the stalk-cutter. (Shown in Fig. 5 of the drawings.) This cutter is provided with a frame, consisting of the bars N and the bars O, the said bars N being provided 20 with bearings in which is journaled the shaft P, to which are secured the cutters Q, R representing a cover adapted to fit over the latter, and secured to the bars O, as shown. When the machine is used for this purpose, a 25 seat, S, may be secured to the axle A.

My invention is exceedingly simple in construction, is durable and efficient in use, and can be manufactured at a small initial cost.

It is evident that slight changes in the construction and relative arrangement of the different parts might be resorted to without departing from the spirit of my invention, and hence I would have it understood that I do not limit myself to the exact construction and 35 arrangement of parts shown and described, but hold myself at liberty to make such alter-

ations therein as fall within the spirit and scope of my invention.

Having fully described my invention, what I claim as new, and desire to secure by Letters 40 Patent, is—

1. The combination, with the arched axle and braces connecting the sides of the end arches of the axle, of standards swiveled to the braces and axle, drag-bars pivotally secured to the standards, and clod-crushers or other suitable implements secured to the drag-bars in such a manner whereby they are allowed to tilt or change their relative positions to the drag-bar, substantially as set forth. 50

2. The combination, with an arched axle and wheels mounted thereon, of braces connecting the sides of the end arches of the axle, standards connecting the braces and axle, drag-bars secured to the standards, and a sectional 55 adjustable yoke connecting the rear ends of the latter, substantially as described.

3. The combination, with an arched axle and wheels mounted thereon, of braces connecting the sides of the end arches of the axle, 60 standards connecting the braces and axle, drag-bars, a yoke, a bell-crank, and a dog adapted to raise and sustain in place the drag-bars, substantially as described.

In testimony whereof I have signed this 65 specification in the presence of two subscribing witnesses.

JOSEPH DIVORA.
